PUMP

Edward J. Ruthman, Cincinnati, Ohio

Application September 11, 1936, Serial No. 100,343

2 Claims. (Cl. 103—104)

This invention relates to improvements in a circulating pump such as is used for circulating lubricant, cooling medium, cutting compound, and the like, relative to a machine tool.

5 One of the principal objects of the present invention is the provision of a circulating pump in which the pump housing is so arranged as to be conveniently attached to a tank, or a machine tool or the like and in which the discharge pipe may be arranged within the tank, machine tool or the like.

Another object of this invention is the provision of a circulating pump in which the intake and exhaust are arranged in close proximity to one another, whereby the pump, as a whole may be mounted so as to utilize the least amount of space.

It is also an object of this invention to provide a novel pump housing which will accomplish the objects above and include otherwise the features of the invention disclosed in co-pending application, Serial No. 81,043.

Other objects and advantages of the present invention should be readily apparent by reference to the following specification considered in conjunction with the accompanying drawings forming a part thereof and it is to be understood that any modifications may be made in the exact structural details there shown and described, within the scope of the appended claims, without departing from or exceeding the spirit of the invention.

In the drawings:

Fig. 1 is a vertical sectional view through a self contained circulating pump showing this invention.

Fig. 2 is a horizontal sectional view taken on line 2—2 of Figure 1.

Fig. 3 is a horizontal sectional view through the pump housing and taken on line 3—3 of Figure 1.

Fig. 4 is a fragmentary sectional view through the lower part of the mechanism of Fig. 1 and includes a portion of a tank or machine tool base and illustrates a modification of the construction of the pump housing.

Fig. 5 is a vertical sectional view illustrating the passage through the pump body taken on line 5—5 of Fig. 4.

Fig. 6 is a vertical sectional view through the lower end of Fig. 1 and illustrates a further modification in a pump housing.

Fig. 7 is a horizontal sectional view taken on line 7—7 of Fig. 6; and

Fig. 8 is an end elevational view of the pump housing of Figs. 6 and 7.

Throughout the several views of the drawings similar reference characters are employed to denote the same or similar parts.

In the past, circulating pumps of the centrifugal type have been produced with the intakes and exhausts radially spaced from one another with respect to the axis of the impeller. By this construction the discharge pipe was located externally of the tank or machine tool with which the pump was employed and this frequently resulted in an inconvenient arrangement of parts. By the present invention, the intake and exhaust are arranged at the same side or face of the pump housing and preferably through the mounting flange for the pump. Various modifications of this arrangement are illustrated in the drawings, to be later described in detail, and this arrangement may be such as to have the intake and exhaust ports co-axial and concentric with each other or laterally spaced with respect to one another.

Specifically referring to the drawings and particularly to Fig. 1 thereof the numeral 10 indicates a motor disposed above a pump indicated by the reference numeral 11. The motor 10 and pump 11 are connected to one another by an extension or connecting housing 12. The motor 10 includes an upper housing 13 and lower housing 14 between which is the stator ring 15. The upper housing 13 is provided with a bearing seat 16 in which is seated the ball bearing 17. The lower housing is likewise provided with a bearing seat 18 in which is seated a ball bearing 19.

Rotated on said ball bearings 17 and 19 is a shaft 20 which extends through the motor 10, connecting housing 12 and into the pump 11. The shaft 20 has secured to it at a point within the stator ring the rotor 21 of the motor. Secured to the shaft 20 immediately beneath the bearing 17 is a fan 22 having a plurality of spaced blades 23. The flange of the fan above the blades 23 is formed into a cup shaped receptacle 24 and the said receptacle is utilized to prevent lubricant, supplied to the bearing 17 through the "oiling" fixture 25, from contacting the motor rotor and stator parts. Any lubricant within the receptacle 24 is centrifugally ejected therefrom against the inner wall 26 of the dome end 27 of the motor housing 13. The lubricant flows through this housing to and through apertures 28 formed through the wall of the motor housing 13 at the bottom of the dome 27. To assist the outward flow of the centrifugally discharged lubri-

cant the lower walls of the aperture 28 extend inwardly towards the fan 22 as illustrated at 29. The inner end of the wall or shelf 29 turns upwardly to provide the lip 30 which is closely adjacent the periphery of the fan. The lip 30 and the shelf 29 in addition intercept any lubricant that would overflow this receptacle 24 and therefore again prevent this excess lubricant from engaging with the motor parts.

10 The lower housing 14 is provided with an oiling duct 31 which terminates at its inner end at the bearing 19 and at its outer end has the "oiling" fixture 32. Beneath the bearing 19 the shaft 20 has secured to it a centrifugal throwout member 15 or vane 33 which prevents mist or spray and the like, rising within the extension housing 12, from engaging the motor parts. This moisture and the like is intercepted by the centrifugal throwout member 33 and discharged through the ducts or 20 ports 34 formed radially through the flange 35 at the upper end of the connecting housing 12. The flange 35 is further provided with a plurality of apertures through each of which projects bolt 36 for connecting the said housing 12 to the motor 25 housing 14.

The lower end of the connecting housing 12 is provided with a radial flange 37 through which projects a plurality of bolts 38 for connecting the extension housing 12 to the pump 11. Projecting 30 below the flange 37 the housing 12 has a sleeve-like extension 39 open at one side as at 40. At the end of the sleeve 39 is a flange 41 having an enlarged central aperture 42. The flange 41 forms the upper side of the impeller chamber 43 35 formed within the pump housing.

The pump 11 includes a pump housing 44 having at its upper side a flange 45 to which the flange 37 of the extension housing is secured. Within the housing 44 is a pair of spaced webs 40 46 and 47 which, together with the flange 41, completes the impeller chamber 43. The webs 46 and 47 terminate at one side of the housing in the discharge pipe 48. The base 49 of the pump housing and the flange 45 each terminate in an attaching flange 50 which is provided axially therethrough with an opening 51.

As seen in Fig. 1 the discharge conduit or pipe 48 projects through the opening 51 in the attaching flange 50 and provides passages entirely 50 around the discharge conduit 48 to the interior of the pump housing 44. These passages 51 form supply ducts or ports for the enlarged aperture 42 in the flange 41 and the enlarged aperture 52 in the web 47 for supplying the impeller chamber 43 with liquid or fluid to be circulated by the pump.

The impeller chamber 43, see Fig. 3, is of the usual construction starting with substantially nothing as at the point 53 and gradually enlarging until the discharge conduit or pipe 48 is 60 reached. Any suitable or desirable impeller may be utilized for circulating the liquid or fluid. As shown in the drawings the impeller illustrated comprises a hub 54 secured to a reduced portion 55 at the end of the shaft 20. Projecting radially 65 from the center of the hub is a disc 56 having secured to its upper and lower surfaces respectively impeller blades 57 and 58. The upper blades 57 of course receive liquid or fluid through the aperture 42 in the flange 41 while the blades 58 receive 70 the liquid or fluid through the aperture 52 in the web 47.

From the foregoing it will now be appreciated that there has now been provided a pump housing in which the pump is supplied with fluid or liquid 75 through openings provided in the mounting flange

50 as is usual construction. At the same time the pump is provided with a discharge conduit or pipe extending through the same mounting flange 50 instead of having this discharge opening radially spaced from the intake opening as is usual construction and is illustrated in co-pending application, Serial No. 81,043 which was filed on May 21, 1936.

By the construction above referred to the pump, as a whole, may be secured by bolts or the like 10 extending through openings 59 in the mounting flange 51 to a sump, tank or machine tool base in which the supply tank is formed and will receive the fluid, liquid or the like to be circulated through an aperture in the wall of the sump, tank 15 or machine tool registering with the supply aperture 51 in the mounting flange 50, as illustrated for example in Fig. 4. Projecting into said sump, tank or machine tool base through the same opening therein is the discharge pipe or conduit 48 20 and to which the discharge pipe extension is connected. From this it will be seen particularly in the case of a machine tool structure, that the discharge pipe may be concealed within the machine tool or may even be formed integral therewith and connected with the discharge conduit 48. In this way the said discharge pipe for the 25 circulating pump will be out of the way and will not interfere with control mechanisms or the like that are usually disposed externally of the machine tool.

In some cases it may be desirable to supply the pump from a second source other than the supply directly through the supply opening 51 in the mounting flange 50. Such a construction is illustrated in Figs. 4 and 5. As shown in these views the space or passage 60 between the web 47 and base 49 of the pump housing, which normally supplies the lower side of the impeller, terminates in a threaded aperture 61 to which the supplementary supply pipe 62 is connected, while the discharge conduit or pipe 48' is vertically spaced with respect thereto. At the same time, the normal supply aperture 51' supplies the upper side of the pump impeller through ports around 35 the discharge conduit or pipe 48'. By this construction, the lower side of the impeller may be supplied from a point, remote from the point of supply of the upper side of the impeller. As an example of the use to which this modified construction can be put, attention is specifically invited to Fig. 4. In this set-up, use is made of a delivery pipe or the like 63, which carries the fluid from the machine tool table to the sump or tank 64. Instead of allowing all of the fluid flowing through said delivery pipe 63 to enter the tank 64, a certain proportion thereof is diverted, by the funnel shaped member 65, to the supply pipe 62, to the under side of the impeller; while the remainder of the fluid passes through apertures 66 40 in the funnel shaped member 65, to the sump or tank 64, and is supplied to the upper side of the impeller, through the aperture or opening 51' in the mounting flange. By this construction also, a vacuum or suction is placed on the delivery pipe 63, thereby causing a more rapid emptying of this pipe and a quicker drainage of the fluid from the machine tool table. It should also be noted that, with this construction, the lower side 45 of the pump may be supplied from a point below the pump by turning the supply pipe 62 to this lower point, and mounting a foot valve on said supply pipe to avoid the loss of pump priming.

A further modification of the pump housing, is illustrated in Figs. 6 to 8 inclusive. In these 50

views, the intake and discharge ports are again arranged at the same side of the pump, but are laterally spaced from one another, instead of being vertically spaced, as in Figs. 4 and 5, or concentric with one another, as in Figs. 1 and 3. 5 This is particularly illustrated in Fig. 7, in which the supply aperture 51" supplies the upper and lower side of the impeller, and extends from one end of the mounting flange inwardly toward the center of the housing, while the discharge conduit or pipe 48" extends from the other end of the mounting flange, toward the center of the housing. 10

In this modification, and as seen in Fig. 6, the lower side of the impeller chamber 43, instead of being completed by the web 47, as in Figs. 1 and 4, is completed by a flange 67, which is similar to the flange 41, of the extension housing 12. The flange 67 is formed at the end of a sleeve 68 projecting from a closure plate 69. The closure plate 69 is provided with a plurality of apertures through which project bolts 70, which also enter a flange 71, on the lower end of the housing, and which flange is similar to the flange 45, on the upper end thereof. 25

It should be noted, that the closure plate attaching bolts 70 are identical with the bolts 38, utilized in securing the extension housing 12 to the pump and, it should further be noted, that the circumferential spacing of the bolts 70 and 38 30 are identical, whereby the housing may be turned end for end and the housing may be positioned to form a right or left hand pump, by merely changing the position of the pump housing about the axis of the shaft 20. In other words, with the construction as illustrated in Figs. 6 to 8 inclusive, the pump may be readily made to take care of right or left hand delivery, by merely adjusting the parts and in some cases by reversing 35 the direction of rotation of the motor rotor 21.

It should also be noted, that the pump housing, illustrated in Figs. 1 and 4 may, instead of having web 47 for completing the impeller chamber and the base 49, be provided with the end closure 40 plate 69.

It is believed, that the foregoing description fully discloses the invention, and provides a structure which will accomplish the advantages and objects initially set forth.

50 What is claimed is:

1. In a circulating pump of the class described, a pump housing casting including an integral mounting flange forming the sole support for the

pump and from which projects the encircling body portion of the housing, which in turn has integral therewith, and interiorly thereof, spaced flanges to form an impeller discharge passage, means associated with said casting, and in at 5 least one instance removably secured thereto, in alignment with the impeller discharge passage flanges and outer edges of the encircling body portion for forming an impeller chamber and for closing the sides of the pump housing, an impeller 10 within said impeller chamber, the impeller chamber sides having formed therethrough supply ports for supplying the interior of the impeller chamber and the impeller and said ports being in communication with an intake port formed 15 through the mounting flange, and said impeller chamber discharge passage flanges beyond the impeller chamber being connected to form a discharge pipe with its axis in the plane of rotation 20 of the impeller and substantially coincident with the axis of the intake port and said discharge pipe passing through the intake port.

2. In a circulating pump of the class described, a pump housing casting including an integral mounting flange forming the sole support for the 25 pump and from which projects the encircling body portion of the housing, which in turn has integral therewith, and interiorly thereof, spaced flanges to form an impeller discharge passage, means associated with said casting, and in at 30 least one instance removably secured thereto, in alignment with the impeller discharge passage flanges and outer edges of the encircling body portion for forming an impeller chamber and for closing the sides of the pump housing, an impeller 35 within said impeller chamber, the impeller chamber sides having formed therethrough supply ports for supplying the interior of the impeller chamber and the impeller and said ports being in communication with an intake port formed 40 through the mounting flange, said impeller chamber discharge passage flanges beyond the impeller chamber being connected to form a discharge pipe with its axis in the plane of rotation of the impeller and substantially coincident with the axis of the intake port and said discharge pipe passing through the intake port, a driving shaft connected with the impeller and projecting from one side thereof, and driving means for said shaft supported by the aforesaid means which forms one side of the impeller chamber and pump housing.

EDWARD J. RUTHMAN.
